US00D911550S

(12) **United States Design Patent** (10) **Patent No.:** **US D911,550 S**
Memic et al. (45) **Date of Patent:** **** Feb. 23, 2021**

(54) **CELL BLOCKER FOR MULTI-WELL CELL CULTURE PLATE**

(71) Applicant: **King Abdulaziz University**, Jeddah (SA)

(72) Inventors: **Adnan Memic**, Macomb, MI (US); **Tuerdimaimaiti Abudula**, Jeddah (SA); **Kalamegam Gauthaman**, Jeddah (SA)

(73) Assignee: **King Abdulaziz University**, Jeddah (SA)

(**) Term: **15 Years**

(21) Appl. No.: **29/709,764**

(22) Filed: **Oct. 17, 2019**

(51) LOC (13) Cl. **24-02**

(52) U.S. Cl.

CLAIM

The ornamental design for a cell blocker for multi-well cell culture plate, as shown and described.

DESCRIPTION

FIG. 1 is a bottom perspective view of a cell blocker for multi-well cell culture plate;

FIG. 2 is a top perspective view thereof;

FIG. 3 is a bottom plan view thereof;

FIG. 4 is a top plan view thereof; and,

FIG. 5 is a side view thereof, all side views being identical.

1 Claim, 5 Drawing Sheets
